(57) **CLAIM**

The ornamental design for a hose storage post, as shown and described.

DESCRIPTION

FIG. 1 is a top, front, left side perspective view of an embodiment of a hose storage post according to the present design. FIG. 2 is a top plan view of the hose storage post shown in FIG. 1.

FIG. 3 is a front elevation view of the hose storage post shown in FIG. 1.

FIG. 4 is a left side elevation view of the hose storage post shown in FIG. 1.

FIG. 5 is a right side elevation view of the hose storage post shown in FIG. 1.

FIG. 6 is a rear elevation view of the hose storage post shown in FIG. 1.

FIG. 7 is an enlarged perspective view of a top portion of the hose storage post shown in FIG. 1; and,

FIG. 8 is an enlarged perspective view of a central portion of the hose storage post shown in FIG. 1.

The broken lines illustrate portions of the embodiment of the hose storage post and form no part of the claimed design.
